UNITED STATES PATENT OFFICE.

RUDOLF KNIETSCH, OF LUDWIGSHAFEN, GERMANY, ASSIGNOR TO THE BADISCHE ANILIN- & SODA-FABRIK, OF LUDWIGSHAFEN, GERMANY, A CORPORATION OF GERMANY.

APPARATUS FOR THE MANUFACTURE OF SULFURIC ANHYDRID.

SPECIFICATION forming part of Letters Patent No. 688,470, dated December 10, 1901.

Original application filed July 14, 1898, Serial No. 685,969. Divided and this application filed November 23, 1899. Serial No. 738,008. (No model.)

To all whom it may concern:

Be it known that I, RUDOLF KNIETSCH, doctor of philosophy, a subject of the King of Prussia, Emperor of Germany, residing at 5 Ludwigshafen-on-the-Rhine, in the Kingdom of Bavaria and Empire of Germany, have invented new and useful Improvements in Apparatus for the manufacture of Sulfuric Anhydrid, of which the following is a specification.

In my application, Serial No. 685,969, of July 14, 1898, I have described the apparatus which is the subject of this application and have included it within the generic claims, 15 and I have filed this as a division of said application for the purpose of securing specific claims for said apparatus.

The form of apparatus here particularly described and claimed is adapted for carrying 20 out the cooling, not by the sulfurous gases, but by means of some other cooling medium, such as air, and the proper amount of heat is transferred from the so-heated cooling medium—say air—by means of proper mechanical appliances to the sulfurous gas to be operated upon. Such mechanical appliances are well known in the art, and their position in the apparatus is merely indicated in these drawings.

30 In the accompanying drawings, Figure 1 is an elevation, partly in section, of an apparatus embodying my invention. Fig. 2 is a similar elevation of a modified form of said apparatus. Fig. 3 is a detail in section of the temperature-regulator.

Fig. 1 shows brickwork M inclosing the wall S², thus forming the annular cooling-space S'. S² may be of sheet-iron. Within the wall S² is the contact-chamber R, containing contact 40 material. (Indicated by the broken section-lines.) h, situated at or near the bottom of the space S', is a source of heat, which is easily and quickly regulatable, such as gas-flames, and serves primarily to heat up the 45 apparatus in order to start the operation, but may be used to maintain the proper temperature in the apparatus for successful working. The fan or ventilator V forces the air used for cooling the contact-chamber through the 50 temperature-regulator G, where the tempera-

ture of the cooling medium is adjusted according to the conditions of temperature existing in the contact-chamber. This temperature-regulator may be constructed as indicated in Fig. 3, wherein the sulfurous gases passing 55 through the pipe E² may be either heated or cooled by a current of fluid of suitable temperature circulating around said pipe within the shell G, which it enters through a pipe e' and leaves through a pipe e². The air or 60 other cooling medium, having its temperature thus suitably regulated, then passes into the cooling-chamber S through E or E', or both. The air or other cooling medium, having cooled the contact-chamber, leaves the cool- 65 ing-chamber S at A, and being at an elevated temperature because of this cooling action the heat contained in it can be used in any suitable manner—as, for example, by transfer to the sulfurous gas to be operated upon. 70 This can be effected by passing this heated air through the heat-interchanger H. The sulfurous gas to be operated upon may pass entirely by way of O through the heat-inter- 75 changer H into F', into D, and then into the contact-chamber R, or partly in this manner and partly directly by way of F' into D and R. The gas containing sulfuric anhydrid leaves the apparatus at C and can then be worked up or used in any suitable way. 80

In Fig. 2 parts corresponding to certain parts of Fig. 1 bear corresponding letters. V represents a fan or ventilator forcing the air through E into the chamber S, where it impinges upon the contact-chamber at its 85 hottest part, thereby energetically cooling the same, and then the so-heated air leaves through A or A', or both, and passes through H, leaving the apparatus at the upper exit, as shown. The gas to be operated upon entering at O can pass through F² into the heat-interchanger H, thereby absorbing heat from the cooling gas, which has become heated through its cooling action, and proceeding through F and D into the contact-chamber R, 90 or the gas can pass directly through O and F or partly by way of O and F and partly by way of O and F² into D and the contact-chamber R. The gas containing sulfuric anhydrid leaves the apparatus at C and can then 95 100

be worked up or used in any suitable way. V^5 , V^6 , V^7 , V^8 , V^9 , V^{10} , V^{11} , and V^{12} are valves for controlling the flow of gas and air through the pipes.

5 I claim—

1. In an apparatus for the manufacture of sulfuric anhydrid by the contact process, in combination with the contact material, a receptacle for the same containing ingress and egress openings, an inclosure forming a cooling-medium passage adjacent to said receptacle, a regulator whereby the temperature of the cooling medium is controlled before entering said inclosure and a transerrer whereby heat contained in said cooling medium after it leaves said passage is communicated to the sulfurous gas to be operated upon.

2. In an apparatus for the manufacture of sulfuric anhydrid by the contact process, in combination with the contact material, a receptacle for the same containing ingress and egress openings, an inclosure forming a cooling-medium passage adjacent to said receptacle and a transerrer whereby heat con-

tained in said cooling medium after it leaves said passage is communicated to the sulfurous gas to be operated upon.

3. In an apparatus for the manufacture of sulfuric anhydrid by the contact process, in combination with the contact material, a receptacle for the same containing ingress and egress openings, an inclosure forming a cooling-medium passage adjacent to said receptacle, a second inclosure forming a second cooling-medium passage adjacent to said first inclosure, means for regulating the temperature of said second passage and a transerrer whereby heat contained in said cooling medium after it leaves a cooling-medium passage is transferred to the sulfurous gas to be operated upon.

In testimony whereof I have hereunto set my hand in the presence of two subscribing witnesses.

RUDOLF KNIETSCH.
